UNITED STATES PATENT OFFICE.

CURT WINKLER, OF NEW YORK, N. Y.

GLOVE.

SPECIFICATION forming part of Letters Patent No. 745,088, dated November 24, 1903.

Application filed September 17, 1903. Serial No. 173,559. (No model.)

To all whom it may concern:

Be it known that I, CURT WINKLER, a subject of the German Emperor, and a resident of the city of New York, borough of Manhattan, 5 in the county and State of New York, have invented a new and Improved Glove, of which the following is a full, clear, and exact description.

The invention relates to gloves having the 10 fingers reinforced at the terminals; and its object is to provide a new and improved glove having the reinforcing portions or tips arranged to present a smooth surface to the wearer's fingers, to prevent uncomfortable 15 contact of the wearer's fingers with projecting edges, seams, or doubled-up portions, at the same time avoiding undue thickening of the glove - fingers, but giving the desired strength and a fine appearance.

20 The invention consists of novel features and parts and combinations of the same, as will be more fully described hereinafter and then pointed out in the claim.

A practical embodiment of the invention is 25 represented in the accompanying drawings, forming a part of this specification, in which similar characters of reference indicate corresponding parts in all the views.

Figure 1 is a plan view of the glove turned 30 inside out. Figs. 2, 3, 4, and 5 illustrate the successive steps for reinforcing a glove-finger, and Fig. 6 is a cross - section of a reinforced glove-finger.

The fingers of the glove consist, essentially, 35 of front and back pieces A A and interposed wedges or fourchettes B, wherever required, and in order to provide each finger with a reinforcing-tip each front and back piece A is provided at its end with an integral extension-flap C, as plainly shown in Fig. 2. The front and back pieces A A are fastened together with the fourchettes B, where required, 40 by a row of stitches D, (see Fig. 3,) and then the extension-flaps C are folded back upon 45 the corresponding front and back pieces A, as illustrated in Fig. 4, to cover up the rounded outer portions of the row of stitches D and to bring the said outer portions of the stitches between the pieces A and the extension-flap, 50 as will be readily understood by reference to Figs. 4 and 6. Each extension-flap C is now

fastened by a row of stitches E or other fastening means—such as an adhesive substance, for instance—to the corresponding front or back piece A, independent, however, 55 of the stitches D.

The finished glove is now reversed to bring the reinforcing-flap C to the inside of the finger, as plainly shown in Fig. 6.

In cutting the blank for the forefinger the 60 flaps C for the front and back pieces remain connected at the outer side, (see Fig. 1,) and in a like manner the flaps C for the inserted thumb remain integrally connected at one side; but the extension-flaps are cut in at 65 their junction with the pieces A, and their outer edges are preferably rounded off, so that when the extension-flaps are folded over onto the pieces A then they readily follow the round outer portion of the row of stitches 70 D and snugly fit onto the surfaces of the pieces A to give a fine finish to the end of the glove - finger and prevent the formation of projecting edges for the ends of the wearer's fingers to rub or abut against, thus avoiding 75 all uncomfortable contact of the wearer's fingers with undesirable sharp projecting edges, seams, or doubled-up portions.

It is expressly understood that the front and back pieces and their fourchettes, where 80 required, are united with each other previous to the turning back of the extension-flaps, so that an exceedingly fine appearance can be given to the glove-finger, both on the outside and on the inside, without the formation of 85 undue projecting edges, especially at the terminals of the glove-fingers. It is further understood that the body portion F of the glove is of usual construction, made from a single piece of material, and the front and rear finger-pieces A A preferably extend integrally 90 from the said single piece, while the thumb is made separate and fastened at the proper place to the body portion F.

By the arrangement described the finger- 95 pieces and their extensions are cut out to the proper shape when forming the blank, and hence no subsequent trimming whatever is necessary, and, furthermore, an exceedingly small amount of material is required and only 100 in the direction of the length of the glove, so that all undue waste of material is prevented.

Having thus described my invention, I claim as new and desire to secure by Letters Patent—

A finger-tipped glove, the fingers whereof consist of front and back pieces connected with each other by a row of stitches, and extension-flaps integral with the front and rear pieces at the ends thereof and beyond the row of stitches, and folded back onto the said pieces and over the row of stitches, to con-

ceal the same, and means for attaching the flaps to the said pieces independent of the rows of stitches, as set forth.

In testimony whereof I have signed my name to this specification in the presence of 15 two subscribing witnesses.

CURT WINKLER.
